UNITED STATES PATENT OFFICE.

JOHN T. WRIGHT, OF KINGSTON, OKLAHOMA, ASSIGNOR OF ONE-THIRD TO W. R. CROW
AND J. R. MAXEY, BOTH OF KINGSTON, OKLAHOMA.

SCISSORS OR SHEARS.

1,137,687.

Specification of Letters Patent. Patented Apr. 27, 1915.

Application filed April 21, 1914. Serial No. 833,480.

To all whom it may concern:

Be it known that I, JOHN T. WRIGHT, a citizen of the United States, residing at Kingston, in the county of Marshall and 5 State of Oklahoma, have invented certain new and useful Improvements in Scissors or Shears, of which the following is a specification.

This invention relates to scissors or 10 shears, designed more particularly for the purpose of cutting sheet metal, and one of the principal objects of the invention is to provide a pair of shears which will cut a piece of sheet metal without requiring one 15 of the severed pieces being supported above the shears at each cut or bite of the same.

Shears for cutting metal as at present constructed, can only be used by lifting or 20 curling the left hand piece of metal as it is cut, and in many instances this kinks or buckles the metal and either entirely destroys it or renders it unfit for use until after it has been passed through flattening rollers.

25 Another object of the invention is to provide a pair of shears in which the pivotal bolt or pin for the two blades is squared to pass through a rectangular opening in one of the blades, and rounded for pivoting the 30 other blade thereto, thus providing a relatively stationary blade and a coacting pivoted blade, eliminating the tendency of the blades becoming separated to interfere with the cutting action of the same.

35 These and other objects may be attained by means of the construction illustrated in the accompanying drawings, in which:

Figure 1 is a side elevation of a pair of shears made in accordance with this invention, Fig. 2 is a top plan view of the same, 40 and Fig. 3 is a detail sectional view taken on the line 3—3 of Fig. 1.

Referring to the drawings, the numeral 1 designates the lower or stationary blade and 45 2 is the pivoted blade. Extending laterally from the heel of the blade 1 is an integral connecting bar 3, and extending upward from the bar 3 is an integral vertical member 4 which is curved at 5 and integrally

connected to the shank 6 which is provided 50 with a handle 7 at its end.

The blade 2 at its heel end is provided with a curved arm 8, which extends backwardly to form the shank 9 which is curved at 10 downwardly and deflected as at 11 to 55 dispose the shank 12 immediately under the shank 6, and said shank 12 being provided with a handle 13. The pivot bolt 14 is squared at 15 to extend through a rectangular opening in the blade 1 and said bolt is 60 rounded at 16 upon which the blade 2 is pivoted, and a nut 17 is fitted on the bolt 14 for holding the two blades in contact.

From the foregoing it will be obvious that the stationary blade 1 will rest upon and 65 hold the piece of metal at the left hand side of the shears and prevent it from curling up at each bite made by the shears, and since the handle members 7 and 13 are disposed in a parallel plane at the right of line 70 of cut, one part of the metal being cut will lie flat upon the table or surface which supports them.

Various changes may be made in the details of construction without departing from 75 the spirit and scope of the invention as defined in the claim.

What is claimed is:

A shears provided with a stationary blade having a transversely disposed bar 80 extending from the heel end of said blade, a vertical member connected to said bar, a shank extending rearwardly from said vertical member and provided with a handle, and a pivoted member comprising a blade 85 having an upwardly and downwardly curved shank deflected to lie in the same plane with the shank of the stationary blade and provided with a handle, said handles being disposed in a plane parallel to 90 the cutting edges of the blade, and a pivot bolt for connecting said blades together.

In testimony whereof I affix my signature in presence of two witnesses.

JOHN T. WRIGHT.
